DESIGN FOR A WALL BRACKET LAMP

Edwin R. Goodman, Shaker Heights, Ohio, assignor to Railley Corporation, Cleveland, Ohio, a corporation of Ohio

Application April 14, 1937, Serial No. 68,784

Term of patent 3½ years

To all whom it may concern:

Be it known that I, Edwin R. Goodman, a citizen of the United States, residing at Shaker Heights, in the county of Cuyahoga and State of Ohio, have invented a new, original, and ornamental Design for a Wall Bracket Lamp, of which the following is a specification, reference being had to the accompanying drawing, forming part thereof, wherein—

Fig. 1 is a view in side elevation of a wall bracket lamp showing my new design; Fig. 2 is a front elevational view thereof, part being shown in section on the line 2—2 with the shade and socket omitted; Fig. 3 is a bottom plan view thereof, with the arm fragmentarily shown and the shade and socket omitted.

The dominant feature of my design resides in the parts shown in solid lines.

I claim:—

The ornamental design for a wall bracket lamp, substantially as shown and described.

EDWIN R. GOODMAN.
